UNITED STATES PATENT OFFICE.

CHARLES W. TREMPER, OF NEW HAVEN, CONNECTICUT, ASSIGNOR TO THE FULLER MFG. CO., OF NEW HAVEN, CONNECTICUT, A CORPORATION.

SHEET-FEEDING MECHANISM.

Application filed August 17, 1922. Serial No. 582,373.

To all whom it may concern:

Be it known that I, CHARLES W. TREMPER, a citizen of the United States, residing at New Haven, in the county of New Haven and State of Connecticut, have invented a new and useful Improvement in Sheet-Feeding Mechanisms; and I do hereby declare the following, when taken in connection with the accompanying drawings and the characters of reference marked thereon, to be a full, clear, and exact description of the same, and which said drawings constitute part of this application, and represent, in—

Fig. 1 a broken plan view of a sheet-feeding mechanism constructed in accordance with my invention.

Fig. 2 a sectional view on the line 2—2 of Fig. 1, the parts being shown as in position ready to receive a sheet.

Fig. 3 a similar view, showing the parts as the sheet is delivered to a printing cylinder.

Fig. 4 a sectional view on the line 4—4 of Fig. 2.

This invention relates to improvement in sheet-feeding mechanism, and, while particularly adapted for use on printing-presses, is adapted for folding machines and for feeding sheet-metal, or other material, which is liable to "buckle" or rebound as it is delivered. In printing-presses in particular, in transferring the sheet from the tape to the cylinders, it is desirable to straighten and to retard the movement of the sheet and gradually bring it to a stop, as it is in position to be gripped by the cylinder fingers. The object of this invention is to provide mechanism which will so straighten and retard the movement of the sheet, and the invention consists in the construction as hereinafter described and particularly recited in the claims.

The construction of the device may be best understood in connection with a description of its operation.

The forward edge of a sheet of paper, or other material, 10, delivered by the usual tapes 11, or other means, enters between a finger 12, mounted in the lower end of a guide-plate 13, and the lower face of a deflector or top guide 14, this deflector being mounted upon an extension 15 of a block 16 adapted to travel on a bar 17 being held in place by a plate 18. The bar is supported by a frame 53, and pivoted to the block

on a stud 19 is a stop-carrier 20, this stop-carrier being provided with a forwardly-extending screw 21 having a head 22 threaded to receive an adjusting screw 23 having a knurled operating head 24, the screw passing through the upper end of the plate 13, which is swivelly connected with the screw by a washer 25, whereby, when the screw 23 is turned up or down, the guide-plate will be moved with it, and it may be held in its adjusted position by a lock-nut 26. The screw 21 may be adjusted in or out by a capstan-nut 27 and when adjusted it may be locked by a set-screw 28 and lock-nut 29. On the stud 19 is a helical spring 30, one end of which enters the stop-carrier 20 and the other enters a tension-adjusting collar 31 having notches 32 to engage with a pin 33 on the stud 19. The normal function of the spring 30 is to exert a constant effort to hold the guide-plate 13 in its retired position, as shown in Fig. 3 of the drawings. Projecting from the outer face of the stop-carrier 20 is a pin 35 which is engaged by a latch 36 pivoted on a stud 37 carried by the extension 15. This stud is encircled by a spring 38 bearing against an adjusting collar 39 formed with notches 40 to engage with a pin 41 in the stud 37, the other end of the spring entering the latch 36 and tending to depress it, this latch being provided with a latching-face 42, to be engaged by the pin 35. In the outer end of the latch 36 is a transverse pin 43 adapted to be engaged by a tripping-block 44 mounted on the end of the bar 17. Mounted on the top of the stop-carrier 20 is a re-setting-arm 45 adapted to engage with a tie-bar 46 to swing the stop-arm 13 from the position shown in Fig. 3 to the position shown in Fig. 2. Pivotedly connected with the top of a block 16 is a long link 47, its other end being mounted on a bolt 48 extending through a slot 49 in a driving-arm 50, and a short link 51 is also connected with the bolt 48 and with a pivot 52 mounted in a frame 53. The bolt 48 carries at its outer end a roller 48^a traveling in the slot 49. The frame 53 is mounted on a driving-shaft 54 and on the tie-bar 46, both of which are supported in brackets 55 on the usual feed-board 56, which has the usual projecting feed-plate 57 extending toward the press-cylinder 58. A duplicate mechanism is arranged at the other side of the machine.

Mounted on the outer end of the driving-shaft 54 is an operating-lever 59 connected by a link 60 with a driving-crank or eccentric 61, which may be located at any convenient point on the machine.

Assuming that a sheet of material is being delivered by the tape 11, its edge will extend between the finger 12 and the deflecting-plate 14 and be thereby straightened, 10 the mechanism being so timed that as it so enters, the arm 50 starts to swing forward, moving the links 47 and 51 and moving the block 16 forward, and this is at a speed slightly less than the speed of the 15 sheet of material being fed. As the block moves outward, however, the roller 48, traveling in the slot 49, approaches its inner end, and the speed of the block 16 will be gradually retarded, so that, as the edge of 20 the sheet approaches the cylinder, it will be brought to a stop against the usual press front guide 62. At this time the pin 43 will contact with the tripping-block 44, which raises the latch, so as to release the pin 35, 25 permitting the spring 30 to rock the stop-carrier 20 and throw the guide-plate 13 upward into its retired position, as shown in Fig. 3 of the drawings. The sheet is then 30 free to be drawn onto the cylinder in the usual way. In the continued movement of the device, the block is drawn rearward into the position shown in Fig. 2, in which the re-setting-arm 45, engaging with the tie-rod 46, turns the stop-carrier 20, with its pin, into 35 position to be engaged by the latch 36, thus re-setting the mechanism ready to engage the next sheet.

I claim:

1. In a sheet-feeding mechanism, the combination with sheet-checking mechanism, including a slotted driving-arm, of means traveling in said slot, and links connected with said traveling means, the opposite end of one of the said links being relatively fixed and the other link connected with a sheet-checking mechanism.
2. In a sheet-feeding mechanism, a frame, a bar projecting forward therefrom, a slotted driving-arm pivotally connected with said frame, a traveling member moving in said driving-arm, a block mounted on said bar, a link connecting said block with said traveling member, and a link connecting said traveling member with said frame, and means carried by said block for guiding a sheet.
3. In a sheet-feeding mechanism, a frame, a bar projecting forward therefrom, a slotted driving-arm pivotally connected with said frame, a traveling member moving in said driving-arm, a block mounted on said

bar, a link connecting said block with said traveling member and a link connecting said traveling member with said frame, means carried by said block for guiding a sheet, including an adjustable guide-plate and a pivotal stop-carrier, and means for moving the arm and carrier at the limits of their longitudinal movement.

4. In a sheet-feeding mechanism, the combination with a bar, of a block sliding thereon, a stop-carrier pivotally connected with said block, a guide-plate mounted in said carrier, a latch for holding said guide-plate in its operative position, and means for moving said block forward at a gradually reducing speed.

5. In a sheet-feeding mechanism, the combination with a bar of a block sliding thereon, a stop-carrier pivotally connected with said block, a screw projecting forward from said stop-carrier, and having a head, an adjusting screw extending through said head, a guide-plate connected with said adjusting screw, a latch for holding the said guide-plate in its operative position, and means for moving said block forward at a gradually reducing speed.

6. In a sheet-feeding mechanism, the combination with a bar of a block sliding thereon, means for moving said block backward and forward at varying speeds, a stud mounted in said block, a stop-carrier mounted on said stud, an adjustable spring on said stud and connected with said carrier, a guide-plate connected with said carrier, and means for rocking the said carrier.

7. In a sheet-feeding mechanism, the combination with a bar of a block traveling thereon, means including a slotted driving-arm and links for moving said block back and forth on said bar, a stop-carrier pivotally connected with said block, a pin mounted in said stop-carrier, a latch adapted to be engaged by said pin, and means for tripping said latch.

8. In a sheet-feeding mechanism, the combination with a bar, of a block traveling thereon, a stop-carrier pivotally connected with said block, a re-setting-arm connected with said carrier, a latch carried by said stop-carrier, a fixed shaft to be engaged by said re-setting-arm, and means connected with said block for moving the said block forward at a gradually reducing speed.

In testimony whereof, I have signed this specification in the presence of two subscribing witnesses.

CHARLES W. TREMPER.
